J. F. MEYER

2,234,770

VIBRATOR

Filed Oct. 28, 1939

UNITED STATES PATENT OFFICE

2,234,770

VIBRATOR

John F. Meyer, Chicago, Ill., assignor to The Exhibit Supply Company, Chicago, Ill., a corporation of Illinois

Application October 28, 1939, Serial No. 301,742

2 Claims. (Cl. 128—33)

This invention relates to certain novel improvements in body vibrating devices, the present invention constituting an improvement over that shown and described in the application of Charles A. Solinski, Serial No. 282,579, filed July 3, 1939, in which Patent 2,174,648 has issued and has for its principal object the provision of an improved construction of this character which will be highly efficient in use and economical in manufacture.

The principal object of the present invention is to provide a body vibrating device in which the operation of the vibrating means is automatically controlled as the person places his or her body on or off of the platform of the device.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a perspective view of a body vibrating device embodying this invention;

Fig. 2 is an enlarged sectional detail view of the same taken substantially on line 2—2 of Fig. 1;

Fig. 3 is a fragmentary perspective view of the means for controlling the circuit of the vibrating means embodied in my invention;

Fig. 4 is a fragmentary plan view of the same taken substantially on line 4—4 of Fig. 2;

Fig. 5 is a fragmentary enlarged sectional detail view of the same taken substantially on line 5—5 of Fig. 4; and

Fig. 6 is a fragmentary sectional detail view of the same taken substantially on line 6—6 of Fig. 5.

Referring to the drawing showing my preferred form of construction, my improved body vibrating device includes a housing 10 of suitable construction comprising a front wall 11 having at its lower edge portion an elongated slot 12 formed therein. This housing 10 is supported by a base 13 having an exterior portion 14. Arranged in superimposed relation with respect to this base 13 is a platform 15 having an interior portion 16 and an exterior portion 17, the interior portion 16 projecting through the slot 12, as shown in Fig. 2.

The outer corresponding end portions 18 of the platform 15 and base 13 are connected together through the medium of a nut and bolt

structure 19 including a rubber washer 20, together forming a fulcrum.

The opposite corresponding inner end portions of the base 13 and platform 15 are resiliently supported in substantially spaced relation with respect to each other by means of a spring structure 21, the limits of expansion of which are controlled by a contraction spring 22 connected to the adjacent end portions of the base 13 and platform 15 as at 23.

On the interior end portion of the platform 15, which end portion is hereinafter referred to for convenience as extended portion, is mounted a vibrating means comprising an electric motor 25 and an eccentric 26, the length of which is varied by an adjustment screw 28, this being accomplished by loosening the lock nut 29 and rotating the screw 28 to enlarge or diminish the length of the eccentric and consequently to enlarge or diminish the degree of vibration.

In machines of this type with which I am familiar, the vibrating means is permitted to rotate through a predetermined period of time. The disadvantage of such an arrangement is found in the fact that when a person steps off of the platform 17, the vibrating device continues to operate. One of the objects of this invention is to remove this objectionable feature. Preferably I overcome this objectionable feature by securing to a wall 30 of the base through the medium of the screws 31 a switch structure 32 comprising a stationary contact member 33 and a flexible contact member 34 operable to make and break a circuit to the motor 25 by means of a toggle arm 35.

This toggle arm 35 as best shown in Fig. 5, has a finger 36 secured thereto as at 37, and this finger has its free end projected through a loop 38 secured to a supporting block 39 carried by the extended portion, as at 40.

The toggle arm 35 is pivotally supported at 41 by spaced ears 42, and the inner end of the toggle arm is bifurcated as at 43 to receive the contact member 35. The stationary and movable contact members 33 and 34 are connected in the electric circuit of the motor 25, as diagrammatically shown in Fig. 4.

In the operation of my invention a person will stand upon the footprint indications 44 formed on the exterior portions 17 of the platform 15. The weight of the person will pivot the platform 15 against the action of the springs 21 about the fulcrum provided by the nut and bolt connection 19 and washer 20. As this platform 15 pivots downwardly, the loop 38 bears 50

upon the arm 36, causing the toggle arm 35 to pivot about its pivot 41. In this pivotal movement of the toggle arm 35, the contact spring member 34 is flexed, bringing it into engagement 5 with the stationary contact 33, thus completing the circuit to the motor 25. This circuit will be complete as long as the person remains with his or her weight on the platform 15.

As soon as this weight is removed from the 10 platform 15, the springs 21 will urge the platform into its normal position, and during this movement into normal position the loop 38 will act upon the arm 36, pivot the toggle arm 35 in a retroactive position, flexing the contact spring 15 member 34 and breaking the engagement between the contact member 34 and the stationary contact member 33.

This loop 38 and finger 36 are formed and related one to the other in a manner such that 20 after the toggle arm has been pivoted by downward movement of the platform due to the weight of the body thereon, there is a sufficient degree of flexibility which will permit the vibratory action of the platform 15 without affecting the thus 25 closed toggle switch.

During the operation of the motor 25, the eccentric 26 will be caused to rotate and impart a vibratory action to the platform 15.

From the description herein taken in connection with the accompanying drawing, it is manifest that the operation of the motor is automatically controlled through the action of the toggle switch, which switch in turn is opened and closed as the weight of a person is disposed upon or 30 removed from the platform 15.

While I have illustrated and described the preferred form of construction for carrying my invention into effect, this is capable of variation and modification without departing from the 35

spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In a vibrating machine including a platform and electrically powered means for vibrating the same, the combination with said platform of a switch in circuit with said electrically powered means to control operation thereof, and switch operating means comprising a loop member attached to the platform to lie 10 in a plane extending in the direction of movement of the platform, and a finger member for operating the switch and projecting from the switch into the loop to be moved by the latter responsive to movement of the platform when a 15 weight is loaded on the platform, whereby to close the switch and energize said electrically powered means.

2. In a device of the class described, a platform operated switch comprising an elongated 25 metal strip constituting one contact, and fixed at one end for movement of an opposite end portion into and out of engagement with a companion contact, a toggle arm pivoted at one side of said strip to extend at right angles thereto 30 with a bifurcated end portion fitted over a mid portion of the strip to flex the latter back and forth for movement relative to said companion contact, and a helical compression spring on said strip acting between the fixed end of the latter 35 and said bifurcated end of the toggle arm to give snap action to the strip responsive to operating movements of the toggle arm.

JOHN F. MEYER.
